(57) **CLAIM**

The ornamental design for an augmented reality glasses, as shown and described.

DESCRIPTION

FIG. 1 is a perspective view of an augmented reality glasses showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view thereof showing the shading cover detached from the glasses;

FIG. 10 is another perspective view thereof showing the shading cover detached from the glasses;

FIG. 11 is a reference view thereof showing the hook attached to the underside of the glasses; and,

FIG. 12 is a reference view thereof showing the hook detached from the underside of the glasses.

The dashed broken lines illustrate portions of the augmented reality glasses that form no part of the claimed design. The oblique line shading shown in the drawings indicates a transparent or translucent surface.
